246,120, now Patent No. 234,037. Divided and
this application Apr. 10, 1974, Ser. No. 459,602

Term of patent 14 years

Int. Cl. D6—06

U.S. Cl. D6—143

Fig. 1.

Fig. 2.

Fig. 3.

Fig. 4.

Fig. 5.

Fig. 6.

FIG. 1 is a front perspective view of a check-out counter or similar article showing our new design.

FIG. 2 is a top plan view thereof.

FIG. 3 is a front elevation view thereof.

FIG. 4 is a back elevation view thereof.

FIG. 5 is a left end elevation view thereof.

FIG. 6 is a right end elevation view thereof.

This is a division of application Ser. No. 246,120, filed Apr. 20, 1972, and now Pat. No. D. 234,037.

We claim:

The ornamental design for a check-out counter or similar article, substantially as shown and described.
